(57) **CLAIM**

The ornamental design for a golf club caddie, as shown and described.

DESCRIPTION

FIG. 1 is a perspective view showing my new design of the golf club caddie in an open, deployed form.

FIG. 2 is a perspective view of the golf club caddie of FIG. 1 showing a golf club bag in broken lines which forms no part of the claimed design.

FIG. 3 is a left view thereof.

FIG. 4 is a right view thereof.

FIG. 5 is a front view thereof.

FIG. 6 is a rear view thereof.

FIG. 7 is a top view thereof.

FIG. 8 is a bottom view thereof.

FIG. 9 is a perspective view of the golf club caddie in a partially open form.

FIG. 10 is a perspective view of the golf club caddie in a closed form.

FIG. 11 is a modified form of the golf club caddie of FIG. 1 which includes a cradle for a wireless remote control and an antenna for receiving wireless signals from the remote control; and,

FIG. 12 is a rear view of the golf club caddie of FIG. 11 which more clearly shows the remote control in its cradle and the antenna.
